(57) **CLAIM**

I claim the ornamental design for a vape pen, as shown and described.

DESCRIPTION

FIG. 1 is perspective view of a vape pen in accordance with the principles of the present disclosure;
FIG. 2 is front elevational view of the vape pen of FIG. 1;
FIG. 3 is a rear elevational view of the vape pen of FIG. 1;
FIG. 4 is right side view of the vape pen of FIG. 1;
FIG. 5 is a left side view of the vape pen of FIG. 1;
FIG. 6 is a top plan view of the vape pen of FIG. 1; and,
FIG. 7 is a bottom plan view of the vape pen of FIG. 1.
The broken lines in the drawings depict portions of the vape pen that form no part of the claimed design.
